United States Patent Office

Des. 192,544
Patented Apr. 3, 1962

192,544

STAPLING MACHINE OR SIMILAR ARTICLE

Robert H. Crowle, Mount Prospect, William G. Crowle, Deerfield, and Charles E. Jones, Evanston, Ill., assignors to Swingline Inc., Long Island City, N.Y., a corporation of New York

Filed Apr. 10, 1961, Ser. No. 64,669

Term of patent 14 years

(Cl. D74—1)

FIG. 1 is a top plan view of a stapling machine or similar article showing our new invention.

FIG. 2 is a bottom plan view thereof.

FIG. 3 is a side elevational view, the side opposite thereto being similar in appearance.

FIG. 4 is a front elevational view thereof.

FIG. 5 is a rear elevational view thereof.

We claim:

The ornamental design for a stapling machine or similar article, as shown and described.
